ARTICLE OF REPOSE FOR SUPPORTING THE BODY OF A PERSON

Anton Lorenz, Boynton Beach, Fla.

Application January 7, 1954, Serial No. 402,703

6 Claims. (Cl. 155—106)

This is a continuation-in-part application of my U. S. patent application Ser. No. 316,277, filed on October 22, 1952, for "An Article of Repose for Supporting the Body of a Person," now abandoned, and my U. S. patent application Ser. No. 316,278, filed on October 22, 1952, for "An Article of Repose for Supporting the Body of a Person," now abandoned.

My invention relates to articles of furniture, and more particularly to adjustable reclining chairs or the like articles of furniture, wherein a structure including a seat and a back-rest coordinated with each other in respect to their movements is rockably mounted on a support.

An object of the present invention is to provide a convenient controlling mechanism for a leg-rest swingably mounted on the seat of a reclining article of furniture of above-described type, by means of which the leg-rest may be propelled forwardly and upwardly at a comparatively great initial speed, when the movable members of the article of furniture are swung from their sitting position into a reclined position, so that the leg-rest reaches a horizontal position when the seat and back-rest are only somewhat inclined.

A further object of the present invention is to equip a reclining article of furniture of above-described type with a controlling mechanism for the leg-rest, which permits a movement of the leg-rest into an elevated position without a movement of the back-rest and seat from the sitting position into a reclined position.

Another object of the invention is to improve on the construction of reclining articles of furniture as now customarily made.

Other objects and structural details of the invention will be apparent from the following description when read in conjunction with the accompanying drawings, forming part of this specification, wherein:

Fig. 1 is a side elevational view of a chair according to the invention, a portion of a side wall being broken away,

Fig. 2 is a side elevational view of a different embodiment of a chair according to the invention, a portion of a side wall being broken away,

Fig. 3 is a side elevational view of another embodiment of a chair according to the invention, a portion of a side wall being broken away,

Fig. 4 is a side elevational view of still another embodiment of a chair according to the invention, a portion of a side wall being broken away,

Fig. 5 is a side elevational view of a further embodiment of a chair according to the invention, a portion of a side wall being broken away,

Fig. 6 is a side elevational view of another embodiment of a chair according to the invention, a portion of a side wall being broken away,

Fig. 7 is a side elevational view of a further embodiment of a chair according to the invention, a portion of a side wall being broken away, and

Fig. 8 is a side elevational view of another embodiment of a chair according to the invention, a portion of a side wall being broken away.

2

Referring now to Fig. 1, 10 generally indicates a support having side walls 12 and 14 connected with each other by cross-bars 16.

A back-rest 18 and the rear end of a seat 20 are pivotally connected with the support 10 at 22. A downward extension 24 rigid with the back-rest 18 is pivoted to the rear end of a lower connecting link 26 at 28. The front end of said lower connecting link 26 is pivoted at 30 to the lower end of a guiding link 32, the upper end of which is pivoted to the support 10 at 34. One end of a front connecting link 36 is pivoted to the lower connecting link 26 at 30, in coaxial alignment with the pivotal connection between the lower connecting link 26 and the guiding link 32. The upper end of the front connecting link 36 is pivoted to the seat 20 at 38. The portion of the support between the pivots 22 and 34 form the stationary link of a constrained linkage and the downward extension 24, the chain of connecting links 26, 36, the seat 20 and the guiding link 32 form the movable links of said constrained linkage. When the back-rest 18 is swung into the extreme reclined position 18' limited by the upper end of a rear wall 40 of the support 10, the seat 20 is brought into the reclined position 20'.

A controlling element or arm 42 swingably mounted on 25 the support 10 at 34 in coaxial alignment with the pivotal connection between the guiding link 32 and the support 10 normally abuts against a nose 44 or the like arranged on the guiding link 32. It is to be considered that the portion of the arm 42 which contacts the nose 44 and 30 the nose 44 itself each constitute an element of an abutting means and that the positions of such elements are interchangeable in this and other embodiments of the invention. The lower end of the controlling arm 42 is pivoted at 46 to the lower end of a controlling link 48, 35 the upper end of which is pivoted at 50 to a leg-rest 52 swingably mounted on the front end of the seat 20 at 54.

A locking device 56 of any suitable type arranged on the pivot 54 may be used for holding the leg-rest 52 in a desired position relative to the seat 20.

Furthermore a locking device 58 of any suitable type connected with the seat 20 at 60 may be used for holding the seat 20 in a desired position relative to the support.

When both locking devices 56 and 58 are released and the back-rest 18 is moved into the reclined position 18', 45 the nose 44 of the guiding link 32 abutting against the controlling arm 42 causes a lifting of the leg-rest 52 into the position 52'. Now, when the locking device 58 is tightened, the back-rest 18, seat 20, leg-rest 52 may be held in the reclined position 18', 20', and 52'.

When the back-rest 18 and seat 20 are in the sitting position (shown in full lines) limited by a stop 62 arranged on the support 10 for cooperation with the downward extension 24 of the back-rest 18, and when the locking device 56 is released, the leg-rest 52 may be lifted 50 into an elevated position 52'', as the controlling arm 42 is in loose and in detachable engagement with the nose 44 of the guiding link 32. Now, the leg-rest 52 may be held in said elevated position 52'' by tightening the locking device 56.

According to the embodiment shown in Fig. 2, the back-rest 118 and seat 120 are pivoted to the support 110 at 122. The downward extension 124 of the back-rest 118 is pivotally connected with the rear end of the lower connecting link 126 at 128. The front end of the lower connecting link 126 is pivoted at 129 with an intermediate link 164, which is pivoted at 131 to a front connecting link 136. The upper end of said front connecting link 136 is pivoted to the seat 120 at 138. A guiding link 132 swingably mounted on the support 110 at 134 is 65 in rigid connection with the intermediate connecting link 164 and an extension 166. According to the embodiment shown in Fig. 2 the guiding link 132, the intermediate 70 link 164 and the extension 166, are pivoted to the support 110 at 134, 164 and 166 respectively.

connecting link 164 and the extension 166 are made of a single piece of material. Said single member 132, 164, 166 may be considered as a controlling member or guiding element swingably mounted on the support at 134 and pivotally connected with a connecting link 126 at 129 for cooperation with the control arm or element 142. The guiding element 132, 164, 166 is swung about its pivot 134 through the connecting link 126 in dependence on movements of the back-rest 118. The guiding element 132, 164, 166 is connected with the seat 120 through the front connecting link 136 for causing swinging movements of the seat 120 in dependence on its own swinging movements.

A roller 168 rotatably mounted on the guiding element 132, 164, 166 (or the extension 166 of the guiding link 132) at 170 is in abutting engagement with a controlling arm 142 swingably mounted on the support 110 at 135 at a point spaced from the pivotal connection 134 of the guiding link 132 or guiding element 132, 164, 166 with the support 110. A controlling link 148 pivoted to the controlling arm 142 at 146 is in pivotal connection with a leg-rest 152 at 150. The leg-rest 152 is swingably mounted on the seat 120 at 154. If desired, the location of the pivotal connection 146 may be changed by inserting the pin into different holes of series of holes arranged in the controlling arm 142 and controlling link 148. When the back-rest 118 is moved into the reclined position 118', the seat 120 is brought into the reclined position 120' through the linkage connecting same. At the same time the roller 168 rolls along the controlling arm 142, whereby the leg-rest 152 is propelled into the position 152'.

As the controlling arm 142 and the roller 168 are in loose engagement, it is possible to swing the leg-rest 152 from the sitting position shown in full lines into an elevated position while the seat 120 and back-rest 118 remain in the sitting position.

Locking means corresponding to the locking means 56 and 58 shown in Fig. 1 may be applied to the chair shown in Fig. 2.

According to the embodiment shown in Fig. 3, the back-rest 318 and seat 320 are swingably mounted at 322 on the support 310 of the chair. The rear end of a link chain comprising the lower connecting link 326 and front connecting link 336 is pivoted to the downward extension 324 of the back-rest 318 at 328. The front end of said link chain 326, 336, is pivoted to the seat 320 at 338. The connecting links 326 and 336 of said link chain are pivotally connected with each other at 330. The upper end of a guiding link 332 is swingably mounted on the support 310 at 334; the lower end of said guiding link 332 is pivoted to the lower connecting link 326 at 329. Thus, the portion of the support between the pivots 322 and 334 forms a stationary link of a constrained linkage while the downward extension 324 of the back-rest 318, the seat 320, the chain of connecting links 326, 336 and the guiding link 332 form the movable links of said constrained linkage.

A leg-rest 352 swingably mounted on the seat 320 at 354 is controlled by the following mechanism: One end of a controlling link 348 is pivoted to the leg-rest 352 at 350. The other end of said controlling link 348 is pivoted at 346 to a controlling element 342 swingably mounted on the support 310 at 335. Said controlling element 342 is in loose abutting engagement with a nose 344 arranged on a controlling arm 372 swingably mounted on the support 310 at 335 in coaxial alignment with the pivotal connection between the controlling element 342 and the support 310. The lower end of the controlling arm 372 is pivotally connected with one end of a controlling link 374 at 376. The other end of said controlling link 374 is pivoted to the downward extension 324 of the back-rest 318 at 378.

When the back-rest 318 is swung from the sitting position shown in full lines into a reclined position, for ex-

ample the extreme reclined position 318' shown in dash lines, on one hand the seat 320 is brought into the position 320' by means of the constrained linkage described above and on the other hand the leg-rest 352 is brought into the position 352' by means of the controlling mechanism 348, 342, 372, 374 controlled by the downward extension 324 of the back-rest 318.

As the controlling element 342 is disengageable from the nose 344 of the controlling arm 372, the leg-rest 352 may be swung by hand without movement of the back-rest 318 and seat 320, for example the leg-rest may be brought from the sitting position 352 into the position 352" while the back-rest 318 and seat 320 remain in their sitting position shown in full lines.

Of course, locking means of a type similar to the locking means 56 and 58 of the chair shown in Fig. 1 may be applied to the chair shown in Fig. 3.

The embodiment shown in Fig. 4 substantially corresponds to the embodiment shown in Fig. 3, i. e. again the back-rest structure 418, 424, the seat 420, the link-chain 426, 436 and the guiding link 432 form the movable links of a constrained linkage, the stationary link of which is formed by the portion of the support 410 between the pivots 422 and 434. Furthermore, again the leg-rest 452 swingably mounted on the seat 420 at 454 is pivotally connected at 450 with a controlling link 448 pivoted to a controlling element 442 at 446. Said controlling element 442 is swingably mounted on the support at 435.

However, the controlling arm 472 connected with the downward extension 424 of the back-rest 418 by the controlling link 474 is swingably mounted on the support 410 at 437 at a point spaced from the pivotal connection 435 between the support 410 and the controlling element 442. A nose 444 of the controlling arm 472 is in loose abutting engagement with the controlling element 442.

The operation of the chair shown in Fig. 4 is substantially the same as the operation of the chair shown in Fig. 3.

Locking means corresponding to the locking means 56 and 58 shown in Fig. 1 may be applied to the chair shown in Fig. 4.

In the embodiment shown in Fig. 5, 519 generally indicates a unit comprising a back-rest 518 and a seat 520 rigid with each other. Said unit 519 is swingably mounted on a support 510 at 522. A downward extension 525 rigid with the unit 519 is pivoted at 528 to the rear end portion of a connecting link 526. The front end portion of said connecting link 526 is pivoted at 530 to a guiding link 532 swingably mounted on the support 510 at 534. The upper end of a controlling arm 542 loosely engaged with the link 532 is swingably mounted on the support 510 at 534 in coaxial alignment with the pivotal connection between said link 532 and the support 510. The lower end of the controlling arm or element 542 is pivoted at 546 to one end of a controlling link 548, the upper end of which is pivoted at 550 to a leg-rest 552 swingably mounted on the seat 520 at 554.

When the unit 519 is swung into the reclined position 519', the leg-rest 552 is brought into the elevated position 552' by the medium of the linkage described above.

The sitting position of the movable members of the chair shown in full lines, is limited by a stop 562 arranged on the support 510 for cooperation with the extension 525 of the unit 519; the extreme reclined position, shown in dash lines, is limited by the upper edge 540 of the rear wall of the support 510 cooperating with the unit 519.

If desired, the leg-rest may be brought into the position 552" while the unit 519 remains in its sitting position shown in full lines. The loose engagement between the controlling arm 542 and the link 532 permits a disengagement of the former from the latter for bringing the leg-rest into said position 552".

A locking device 556 of any suitable type arranged on the pivot 554 between the leg-rest 552 and the seat 520 may be used for holding the leg-rest 552 in a desired position relative to the seat 520.

Furthermore, a locking device 558 of any suitable type connected with the seat 520 at 560 may be used for holding the seat 520 in a desired position relative to the support.

According to the embodiment shown in Fig. 6, again the unit 619 having an extension 625 is swingably mounted on the support 610 at 622. The extension 625 is pivoted at 628 to a connecting link 626 which at its other end portion is pivoted at 630 to a link 632 swingably mounted on the support 610 at 634. An extension 672 of the connecting link 626 projecting beyond the pivot 630 is in loose abutting engagement with a controlling arm 642 swingably mounted on the support 610 at 635 at a point spaced from the pivotal connection 634 between the link 632 and the support 610. Again said controlling arm 642 is pivoted at 646 to one end of a controlling link 648, the other end of which is pivoted at 650 to a leg-rest 652 swingably mounted on the seat 620 at 654.

The movement of the unit 619 into the reclined position 619' brings the leg-rest 652 into the position 652'. Furthermore, owing to the disengageability of the controlling arm 642 and the extension 672 of the connecting link 626 the leg-rest 652 may be lifted without a movement of the unit 619, for example into the position 652''.

Locking means corresponding to the locking means 556 and 558 of Fig. 5 may be applied to the chair shown in Fig. 6.

According to Fig. 7 the extension 725 of the unit 719 swingably mounted on the support 710 at 722 carries a roller 769 loosely engaged with a controlling arm 742 swingably mounted on the support 710 at 734. A controlling link 748 is pivoted at 746 to the controlling arm 742 and at 750 to the leg-rest 752 swingably mounted on the seat 720 at 754.

Upon a movement of the unit 719 from the sitting position limited by a stop 763 arranged on the support 710 into the reclined position 719' limited by the upper edge 740 of the rear wall of the support 710, the roller 769 rolls along the arm 742 causing a swinging movement of the latter for bringing the leg-rest 752 into the position 752'. Furthermore, the leg-rest 752 may be brought into the position 752'' while the unit 719 remains in its sitting position.

Again locking means corresponding to the locking means 556 and 558 of Fig. 5 may be applied to the chair shown in Fig. 7.

According to the embodiment shown in Fig. 8 the rollers 869 carried by the extension 825 of the unit 819 swingably mounted on the support 810 at 822 is in loose abutting engagement with one arm 841 of a controlling element 842 being in the shape of a bell-crank lever and being swingably mounted on the support 810 at 834. The other arm 843 of said controlling element 842 is pivoted at 846 to one end of a controlling link 848, the other end of which is pivoted at 850 to a leg-rest 852 swingably mounted on the seat 820 at 854.

During a movement of the unit 819 from the sitting position into the reclined position 819' the leg-rest 852 is brought into the position 852'.

If desired the leg-rest may be brought into an elevated position, for example the position 852'', while the unit 819 remains in its position, for example the sitting position; the arm 841 may be disengaged from the roller 869.

Locking means corresponding to the locking means 556 and 558 shown in Fig. 5 may be applied to the chair shown in Fig. 8.

I have described preferred embodiments of my invention, but it is understood that this disclosure is for the purpose of illustration and that various changes in

shape, proportion and arrangement of parts, as well as the substitution of equivalent elements for those herein shown and described may be made without departing from the spirit and scope of the invention as set forth in the appended claims.

Although in all of the embodiments shown in the drawings the abutting surfaces on the controlling element and on the cooperating element of the rockable structure are disengageable, it would also be possible to eliminate such a disengageable arrangement; for example, a pin and slot connection could be used instead, such a pin and slot connection permitting a slideable relative movement between the members, but preventing a disengagement of the associated members.

15. What I claim is:

1. A reclining chair comprising a support, body-supporting means including a back-rest and seat rockably mounted on said support, a first control element pivotally mounted on said support and coupled to said body-supporting means so as to be movable by said body-supporting means, a second control element pivotally mounted on said support, a second abutment on said second control element for selectively cooperating with said first abutment on said first control element, said second control element being movable independently of said first control element, a leg-rest operatively connected to said seat, leg-rest control means operatively connected to said second control element and to said leg-rest for moving said leg-rest to various elevated positions in response to reclining movement of said back-rest, said leg-rest being coordinated to said back-rest through said first and second control elements and their respective first and second abutments which are in contact with each other, said second control element and said leg-rest control means providing an independent mounting for said leg-rest allowing the occupant of the chair to move said leg-rest to various elevated positions independently of reclining movement of said back-rest, and means operatively connected between said leg-rest and said seat for locking said leg-rest to said seat in various elevated positions to which said leg-rest is brought independently of said reclining movement, said back-rest and seat being movable independently of said leg-rest when said leg-rest is locked in an elevated position wherein said first and second abutments are separated from each other.

2. A reclining chair according to claim 1 wherein said first and second control elements are pivotally mounted on said support at spaced apart locations.

3. A reclining chair according to claim 1 wherein said first and second control elements are coaxially mounted on said support.

4. A reclining chair comprising a support, body-supporting means including a back-rest and seat mounted on said support for reclining and inclining movement respectively, a first control element pivotally mounted on said support and coupled to said body-supporting means so as to be movable by said body-supporting means, a first abutment on said first control element, a second control element pivotally mounted on said support, a second abutment on said second control element for selectively cooperating with said first abutment on said first control element, said second control element being movable independently of said first control element, seat control means operatively connected to said back-rest and to said seat for effecting inclining movement of said seat in response to reclining movement of said back-rest, a leg-rest operatively connected to said seat, leg-rest control means operatively connected to said second control element and to said leg-rest for moving said leg-rest to various elevated positions in response to reclining movement of said back-rest, said leg-rest being coordinated to said back-rest through said first and second control elements and their respective first and second abutments which are in contact with each other, said second control

element and said leg-rest control means providing an independent mounting for said leg-rest allowing the occupant of the chair to move said leg-rest to various elevated positions independently of reclining movement of said back-rest, and means operatively connected between said leg-rest and said seat for locking said leg-rest to said seat in various elevated positions to which said leg-rest is brought independently of said reclining movement, said first control element and said seat-control means providing for the independent inclining movement of said seat in response to reclining movement of said back-rest when said leg-rest is locked in an elevated position wherein said first and second abutment are separated from each other.

5. A reclining chair according to claim 4 wherein said seat control means includes a link pivotally connected to said first control element and to said seat.

6. A reclining chair according to claim 4 wherein said seat control means includes a series of interconnected links connected to said back-rest and to said seat.
